B. M. WALPOLE

ANNEALING APPARATUS

Filed March 11, 1920

Inventor
Benjamin M. Walpole.

By *Howard C. Barlow*
Attorney.

UNITED STATES PATENT OFFICE.

BENJAMIN M. WALPOLE, OF PROVIDENCE, RHODE ISLAND, ASSIGNOR TO NATIONAL GAS FURNACE COMPANY, OF PROVIDENCE, RHODE ISLAND, A CORPORATION OF RHODE ISLAND.

ANNEALING APPARATUS.

Application filed March 11, 1920. Serial No. 364,874.

To all whom it may concern:

Be it known that I, BENJAMIN M. WALPOLE, a citizen of the United States, and resident of the city of Providence, in the county 5 of Providence and State of Rhode Island, have invented certain new and useful Improvements in Annealing Apparatus, of which the following is a specification.

This invention relates to an improved annealing apparatus more particularly adapted for operating upon metal parts; and the object of this invention is to provide a simple apparatus of this character, whereby steam may be applied to the work for the purpose 15 of annealing it.

A further object of the invention is the application of a medium of a lower temperature for cooling the work.

The nature and advantages of the invention will be better understood when the following detailed description is taken in connection with the accompanying drawings, the invention residing in the combination and arrangement of parts as claimed.

In the drawings forming part of this specification, like numerals of reference indicate similar parts in the several views and wherein:—

Figure 1 is a side elevation partly in section illustrating my improved annealing apparatus.

Figure 2 is a top view of the work receptacle, illustrating the means by which the cover is secured in position thereon.

Figure 3 is a perspective view of the check valve which may be used to control the steam outlet.

It is found in the practical operation of annealing furnaces or apparatus to be necessary to exhaust the atmosphere from the work receptacle before applying the heat to the work therein in order to prevent oxidization of the metal. To accomplish this in a simple and effective manner I have provided 40 means whereby steam is admitted to the work-chamber to first drive out the atmosphere and then act upon the work to anneal it, means also being provided for subsequently slowly cooling the work by the application 45 of a medium of lower temperature.

The following is a detailed description of one form of apparatus adapted to perform the functions of my invention in which:—

10 designates a base-plate supported on 55 legs 11 and on which plate is mounted an

outer casing 12, its upper end being provided with a supporting lip 13 on which rests the flange 14 of a lining member 15.

Between this outer casing and lining member is deposited a heat-insulating filling 16 such as asbestos or the like, and an outlet or discharge tube 17 is arranged to pass through the outer wall 12, the filling 16 and the wall of the lining member 15 for the purpose of permitting the escape of the heating medium 60 within. An inner work-carrying receptacle 18 is mounted in the chamber formed by this lining member, this receptacle being of a size to provide a space 19 between it and the lining member for the purpose presently described, and the upper edge of this work receptacle is provided with a laterally-extending flange 20 which rests upon the flange 14 of the lining member.

An inner cover 21 is provided for this receptacle and an outer cover 22 is adapted to close the whole, the same being provided with a laterally-extending flange 23 which has extensions 24 adapted to project under the overlapping locking-lips 25 connected to 75 the sides of the outer casing, whereby this outer cover may be positioned and then by a partial turn cause its lugs to pass beneath the locking hooks to firmly secure this cover in position to withstand the necessary strain 80 due to the internal pressure of steam.

A screw 26 is threaded through this outer cover to engage the inner cover 21 and bind and hold it in position to close the inner 85 work-receptacle.

This work-receptacle is provided with a plurality of holes 27 at its lower edge through which the steam therein may escape into the outer chamber 19 to form a steam-jacket to assist in heating the work-receptacle.

In order to supply this work-receptacle with steam at the desired temperature I have provided an inlet pipe 28 through which steam is admitted from the main 29 leading 90 from a boiler or any desired source of supply. This pipe enters the heating chamber 30 and is arranged in a coil 31 therein, the upper end of which coil passes by way of pipe 32 directly into the work-chamber 33. 95

This coil may be arranged to be heated by any suitable means but I have shown a gas supply pipe 34 which is provided with suitable burners 35 for superheating the steam 100 in the coil to bring it up to an annealing 110

temperature before it is admitted to the work-chamber 33.

In order to cool the work after it has been annealed by the high temperature steam, I 5 close the valve 36 and open valve 37 thereby permitting the steam of lower temperature from the main to pass through pipe 38 into the work-chamber whereby the temperature of the work is gradually reduced to the degree desired.

In order to facilitate or hasten the cooling operation I have provided a water inlet pipe 39 which is adapted to supply a small stream of water to the inlet pipe 38 for the purpose 15 of ejecting a spray onto the work.

In the operation of my improved apparatus it is only necessary to deposit the work into the inner work-chamber 33, then position and lock the covers, next by opening 20 valve 36 the steam is admitted to the coil 31 to be superheated or heated to the desired annealing temperature on its way to the work-chamber, after acting upon the work the steam passes out through the holes 27 into 25 chamber 29 which now serves as a steam jacket to assist in raising the temperature of the work-chamber.

The steam is then discharged from this jacket through the pipe 17. After the flowing 30 superheated steam has been caused to act upon the work for a sufficient length of time which is determined by suitable means such as the usual pyrometer or the like (not herein shown) the valve 36 is closed and the 35 cooler steam is admitted to this work-chamber to slowly reduce the temperature of the work to the desired degree after which the covers are taken off and the work removed from the receptacle and a fresh batch deposited therein.

The device is very simple in construction and is most effective in its operation, and by its use the atmospheric air is driven out and excluded from the work-chamber during 45 the annealing operation thus permitting the annealing action of the steam upon the work to be most effective.

In some cases a check valve 40 may be used on the upturned end 41 of the discharge pipe for maintaining a small pressure in the chamber 33 during the annealing and cooling operations, which valve at the same time positively prevents a back or inward draft of atmosphere from the outside of this chamber through the outlet opening. Then again by the use of this check valve a plus pressure in the chamber is also insured to positively prevent the outside atmosphere from entering through any 55 leak which may be in the apparatus.

The foregoing description is directed solely towards the construction illustrated, but I desire it to be understood that I reserve the privilege of resorting to all the 60 mechanical changes to which the device is

susceptible, the invention being defined and limited only by the terms of the appended claims.

I claim:

1. An annealing apparatus comprising a 70 work-receiving chamber, and means for introducing a non-oxidizing medium into and causing it to circulate through said chamber for raising its internal temperature to an annealing heat.

2. An annealing apparatus comprising a work-receiving chamber, means for introducing steam at an annealing temperature to the work in said chamber for the purpose of annealing the same, and means for 80 introducing a cooling medium to the work while in said chamber.

3. An annealing apparatus comprising a heater for raising the temperature of a non-oxidizing medium to an annealing heat, a 85 work-receiving chamber, and means for exclusively heating said chamber by the introduction of said heating medium.

4. An annealing apparatus comprising a work-receiving chamber, means for introducing a non-oxidizing medium to said chamber for exclusively raising its internal temperature to an annealing heat, and means for introducing cooling medium to said chamber. 90

5. An annealing apparatus comprising a heater for raising the temperature of a non-oxidizing medium to an annealing heat, a work-receiving chamber removed from the direct heating effect of said heater, means for passing said medium into said work chamber at an annealing temperature to act upon the work therein, and means for causing said medium to circulate through said work chamber. 100

6. An annealing apparatus comprising a heater for raising the temperature of a non-oxidizing medium to an annealing heat, a work-receiving chamber removed from the direct effect of said heater, means for passing said medium into said work chamber at an annealing temperature to act upon the work therein, means for causing said medium to circulate through said work chamber, and means for cooling said chamber. 110

7. An annealing apparatus comprising a heater for raising the temperature of a non-oxidizing medium to an annealing heat, a work-receiving chamber removed from the direct heating effect of said heater, means for passing said medium into said work chamber at an annealing temperature to act upon the work therein, means for causing said medium to circulate through said work chamber, and means for introducing a 120 cooler medium into said work chamber to cool the work and chamber.

8. An annealing apparatus comprising a work-receiving chamber, means for applying steam direct to the work in said chamber 125

for the purpose of annealing the same, and means for cooling the work in said chamber by the introduction of a water spray.

9. An annealing apparatus comprising a work-receptacle having a vent opening, means for continuously passing steam at an annealing temperature through said receptacle, and means for shutting off the heating steam and admitting a cooling medium.

10. An annealing device comprising a steam-jacketed work-receiving chamber, and means for applying steam at an annealing temperature to the work in said chamber.

11. An annealing device comprising a steam-jacketed work-receptacle, means for conducting steam at an annealing temperature first through said receptacle and then through said jacket.

12. An annealing device comprising a

steam-jacketed work-receptacle, an outer 20 casing supporting heat-insulating material about said jacket, and means for conducting steam at an annealing temperature through said receptacle and jacket.

13. An annealing apparatus comprising a work-receiving chamber having a vent opening, means for passing steam through said chamber to exclude the atmosphere therefrom and act upon and anneal the work therein, and a check valve to prevent the 30 outside atmosphere from entering through said vent.

In testimony whereof I affix my signature in the presence of two witnesses.
